UNITED STATES PATENT OFFICE

2,478,567

TOY MACHINE GUN OPERATING
MECHANISM

Charles F. Clark, Albuquerque, N. Mex.

Application May 22, 1947, Serial No. 749,784

5 Claims. (Cl. 42—57)

1

The present invention relates to new and useful improvements in toy machine guns and more particularly to an operating mechanism for feeding and firing percussion caps carried by a tape.

An important object of the present invention is to provide an operating mechanism for toy machine guns embodying a frame on which a roll of tape is supported together with feed means for feeding the tape in the path of a hammer for exploding the caps carried by the tape, all of such parts being constructed and arranged as a unitary structure to be housed in a toy machine gun.

A further object is to provide an operating mechanism of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the operating mechanism;

Figure 2 is a top plan view;

Figure 3 is a vertical sectional view taken on a line 3—3 of Figure 1;

Figure 4 is a transverse sectional view of the tape guide taken on a line 4—4 of Figure 1;

Figure 5 is a transverse sectional view showing the hammer for firing the caps and taken on a line 5—5 of Figure 3;

Figure 6 is a fragmentary sectional view taken on a line 6—6 of Figure 3;

Figure 7 is an enlarged perspective view of the feed roller and cam carried at one end thereof for actuating the hammer;

Figure 8 is an enlarged fragmentary perspective view of the hammer, and;

Figure 9 is an end elevational view of the assembled operating mechanism.

Referring now to the drawings in detail wherein for the purpose of illustration I have disclosed a preferred embodiment of the invention, the numeral 5 designates an inverted substantially U-shaped frame including a relatively short leg 6 and a relatively long leg 7. Bearing arms 8 project laterally from each of the legs and in which a shaft 9 is journaled, one end of the shaft being provided with a crank handle 10.

A feed drum or wheel 11 is suitably secured to

2

the shaft 9 adjacent its other end and also suitably secured to the shaft at one end of the feed drum 11 is a cam constructed of a plurality of radially extending cam arms 12. The intermediate portion of the feed drum 11 is formed with circumferentially spaced lugs or teeth 13.

A stationary shaft 14 projects inwardly from the lower portion of the long arm 7 for supporting a roll of percussion caps 15 and comprising a tape 16 on which the caps 17 are carried at longitudinally spaced intervals.

The free end of the tape 16 extends upwardly through a channel-shaped guide 18, the upper portion of the guide being curved around the outer periphery of the drum 11 as shown at 19 and is suitably secured to one edge of the upper portion of the frame 5. The side edges of the guide are formed with inwardly projecting flanges 20 to slidably receive the edges of the tape 16 and to provide a longitudinally extending slot between the flanges to accommodate the movement of the teeth or lugs 13 therein which engage central apertures 21 spaced longitudinally in the tape 16 to thus feed the tape through the guide 18 and over the drum 11.

After leaving the drum 11 and the upper end of the guide 19 the tape 16 with the caps 17 on the upper surface thereof pass under the top of the frame 5 which serve as an anvil against which the caps 17 are struck by a hammer 22 carried at the free end of a resilient arm 23 and which is secured to the upper portion of the frame 5 with a spacing block 24 between the frame and the resilient arm 23.

The free end of the arm 23 projects into the path of the cam arms 12 during rotation of the drum 11 whereby to periodically flex and release the arm 23 and thus cause the hammer 22 to strike the tape and explode the caps 17 as the same passes under the frame 5.

The upper portion 19 of the guide 18 feeds the tape in a straight path for proper engagement of the opening 21 therein by the teeth 13 and in proper position for firing the caps by the hammer 22.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully compre-

hended by the spirit of the invention as herein described and the scope of the appended claims.

Having described the invention, what is claimed as new is:

1. A toy machine gun operating mechanism comprising a U-shaped frame, a hammer including a spring arm secured to one end of said frame and in position to strike against the frame, a shaft including a crank handle journaled in the frame below said hammer, a feed drum carried on the shaft and feeding a tape of explosive caps in the path of the hammer, teeth on said drum engaging the caps and carrying them forward between said hammer and frame and cam arms secured on said shaft adjacent said drum to engage said hammer and cause it to strike said explosive caps.

2. The combination of claim 1 wherein said frame includes a longer leg adjacent the hammer, and a stationary shaft extending inwardly and supporting a roll of explosive caps thereon.

3. The combination of claim 2 wherein a guide channel for said caps is secured to said frame and depends therefrom to guide said caps from the stationary shaft through said hammer.

4. A toy machine gun operating mechanism comprising a U-shaped frame, a hammer including a spring arm secured to one end of said frame and in position to strike against the frame, a

shaft including a crank handle journaled in the frame below said hammer, a feed drum carried on the shaft and feeding a tape of explosive caps in the path of the hammer, teeth on said drum engaging the caps and carrying them forward between said hammer and frame and cam arms secured on said shaft adjacent said drum to engage said hammer and cause it to strike said explosive caps.

5. The combination of claim 4 wherein said frame includes a longer leg adjacent the hammer, and a stationary shaft extending inwardly and supporting a roll of explosive caps thereon.

CHARLES F. CLARK.
